An ornamental design for a four-way buckle or similar article, as shown.

DESCRIPTION

FIG. 1 is a top perspective view of an ornamental four-way buckle or similar article according to the invention.

FIG. 2 is a top plan view thereof.

FIG. 3 is a side view thereof, the other opposing side view being identical.

FIG. 4 is a bottom plan view thereof; and,

FIG. 5 is an end view thereof, the other opposing end view being identical.

The broken line portions of the Figures are for illustrative purposes only and form no part of the claimed design.
